UNITED STATES PATENT OFFICE.

DEWITT C. MCCOY, OF BUSHNELL, FLORIDA.

CAR-COUPLING.

SPECIFICATION forming part of Letters Patent No. 399,278, dated March 12, 1889.

Application filed July 23, 1888. Serial No. 280,729. (No model.)

To all whom it may concern:

Be it known that I, DEWITT C. MCCOY, of Bushnell, in the county of Sumter and State of Florida, have invented certain new and useful Improvements in Car-Couplings; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in car-couplers, and more particularly to that class of couplers known as "link-and-pin" couplers.

The object of my invention is to provide an improved automatic car-coupler which shall be more simple and effective in operation and more durable and composed of fewer parts than the car-couplers heretofore in use. By my construction the coupling is automatically effected when the cars come together, and can be uncoupled from the sides or top of the car without in any way endangering the life or limb of the railroad employés or others, and the coupler is so cheap and simple in construction that it can be adopted by all railroads at a minimum expense.

With these ends in view my invention consists in certain novel features of construction and combinations of parts, more fully described hereinafter, and particularly pointed out in the claims.

Referring to the accompanying drawings, Figure 1 is a perspective view of the end of a car provided with the improved coupler. Fig. 2 is a detached plan view of the vertically-movable cross head or bar carrying the coupling-pin. Fig. 3 is a longitudinal section of the draw-head, showing the spring-actuated block operating longitudinally in the same; and Fig. 4 is a detail view of one end of the vertically-movable cross-bar.

In the drawings, the reference-letter A indicates a draw-bar provided with the usual longitudinal opening or socket, *a*, to receive the link *B*, and with the transverse opening *a'* for the passage of the coupling-pin *C*. A sliding block, *D*, is located in said hollow draw-

bar to the rear of the transverse opening *a'*, and said block is constantly pressed to the limit of its outward movement by a suitable spring, *D'*, interposed between the rear end of block *D* and the inner end of the opening in the draw-bar. The horizontal sides of the draw-bar are provided with longitudinal slots *b b*, in which are confined the pins or lugs *b'*, projecting from the sides of the spring-block *D* through said slots, whereby the backward and forward movements of the block are limited. When the block is pushed to the limit of its forward movement by its spring, it will extend beyond and close the passage for the coupling-pin, and when the block is at its limit of rearward movement the passage for the coupling-pin is open to allow for the free passage of the same. The outer end of the spring-block is beveled inwardly toward the center, as shown, and for the purpose herein-after set forth.

The coupling-pin is guided and carried by a vertically-operating cross head or bar, *E*, extending across the end of the car and having handles *e e*, extending beyond the sides of the car. Said cross-head is loosely confined to the end of the car to allow vertical movement by the vertical guides or yokes *F*, secured to the car and embracing the opposite ends of the cross-head, and the cross-head is provided with lugs *f f* to prevent longitudinal movement and with notches *f' f'* in its lower edge, in which the lower portions of said yokes fit when the cross-head is in the position shown in Fig. 1.

As the ends of the cross-head are confined at the end of the car, the center of the same is curved or arched outwardly, as shown, to bring it over the draw-bar, and at its outwardly-curved portion the cross-head is provided with the forwardly-projecting perforated arm *g*, through which the coupling-pin extends.

G indicates a chain secured to the coupling-pin and extending to the top of the car, as shown, and provided with a stop, *P*, to limit its upward movement.

H indicates a link-holder and guide, consisting of an integral rod journaled on the end of the car and provided with handles upon both sides of the same. At its center said

holder extends outwardly around and in front of the draw-bar, as shown at g' , and directly in front of the opening in the draw-bar the link-holder is provided with the downwardly-bent portion g^2 , in which the link rests and by which it is guided into the opposite draw-head when the cars are coming together.

- In operation, when two cars are to be coupled the coupling-pin of one is withdrawn to allow the spring-block to pass outwardly and close the coupling-pin passage, the lower end of the pin resting upon the upper surface of the block. As the cars come together, the link of the opposite coupler is guided by the holder H into the draw-head and strikes the spring-block and is guided by the bevel edges of the same to its center, so that the full force of the link will be felt to force back the block to allow the pin to fall and effect the coupling.
- It will be readily seen that the cars can be uncoupled either from the top by lifting the pin by the chain attached to the same, or from either side of the car by lifting one end of the cross-head by one of its handles.
- The advantages, utility, and cheapness of the herein shown and described coupler can be readily seen by all persons; hence it is not deemed necessary to fully enumerate the same herein.
- What I claim is—
1. In combination, a draw-bar, a coupling-

pin, a vertically-movable cross head or bar curved or arched outwardly at its center and extending across the end of a car, an arm projecting forwardly from said cross-bar and carrying the coupling-pin, and vertical yokes secured to the car and embracing the ends of said cross-bar, by which the same is loosely confined to the car and rendered vertically movable, substantially as described.

2. In a car-coupler, the combination of a draw-bar provided with a spring-actuated block, a coupling-pin, a vertically-movable cross-head extending across the end of a car and provided with handles at its ends and with a forwardly-projecting arm carrying the coupling-pin, and vertical yokes secured to the end of the car near the opposite ends of and loosely confining the cross-head to the car to allow the head a suitable vertical movement within the yokes, said cross-head being provided with notches in which the ends of the yokes rest and with pins or projections to prevent longitudinal movement of the same, substantially as described.

In testimony that I claim the foregoing as my own I affix my signature in presence of two witnesses.

DEWITT C. MCCOY.
